CLAIM

The ornamental design for a shoe, as shown and described.

DESCRIPTION

FIG. 1 is a top and side perspective view of a shoe according to my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The dash-dot-dash broken line defines a boundary of the claimed design and forms no part of the claimed design.

The broken lines shown represent subject matter that forms no part of the claimed design.

1 Claim, 4 Drawing Sheets(56)
